UNITED STATES PATENT OFFICE.

EMORY SUDLER AND CHARLES E. SUDLER, OF TARRYTOWN, NEW YORK.

AUTOMATIC REGISTER FOR LIQUIDS.

1,418,495.

Specification of Letters Patent. Patented June 6, 1922.

Original application filed March 19, 1920, Serial No. 367,045. Divided and this application filed March 5, 1921. Serial No. 449,690.

To all whom it may concern:

Be it known that EMORY SUDLER and CHARLES E. SUDLER, citizens of the United States, residing at Tarrytown, in the county 5 of Westchester and State of New York, have invented certain new and useful Improvements in Automatic Registers for Liquids, of which the following is a specification.

The present invention relates to quantity 10 and value indicating means for gasoline filling pumps and constitutes a divisional portion of our parent application, Serial No. 367045.

The principal object of the invention is to 15 provide a device which will automatically indicate the amount and value of liquid dispensed, enabling the consumer to ascertain for himself the exact amount of liquid received by him and correspondingly the cost 20 of this amount.

Another object of the invention is to provide quickly detachable and replaceable computing dials carrying indicia to prominently display the current price of the liquid in 25 conjunction with the indicia which indicates the amount and value of liquid dispensed.

Other objects of the invention will be apparent from the following description taken 30 in connection with the accompanying drawings, wherein:

Fig. 1, is a front elevational view of a device constructed in accordance with this invention, parts thereof being broken away 35 to disclose details.

Fig. 2, is a perspective view of the computing mechanism and the co-related float.

Fig. 3, is a detail fragmentary elevational view, partly in section of the computing 40 mechanism.

Fig. 4, is a detail sectional view of a portion of the computing mechanism.

Fig. 5, is a detail fragmentary sectional view showing to advantage the stop for the 45 hook member, a portion of the latter being shown fragmentarily, and

Fig. 6, is a fragmentary side elevational view of the computing dials used in this invention.

The device of this invention consists of 50 a stand generally designated 7, in the present instance being of substantially cylindrical configuration and formed to provide a base 8, intermediate measuring receptacle or 55 chamber 9, upon which is superimposed a

casing 10. The casing 10 is shown in the drawings to be formed integral with the receptacle 9, and preferably is made of metal. Since it is necessary that the contents of the receptacle 9 be visible, a transparent 60 panel, (not shown in the drawings) may be mounted in the receptacle. Or, if desired, the receptacle may be made of glass or other transparent material.

Arranged beneath the stand 7 is a gasoline 65 working tank 11, which has communicating therewith a liquid supply pipe 12, and a vent pipe 13. Both of these extend upwardly through the base 8, as does also a compressed air pipe 14, the three pipes engaging a valve 70 15 which is arranged at the juncture of the receptacle 9 and base 8.

A float 35 is movably mounted in the measuring tank 9, and is guided in its movement through the receptacle by pipes 16 and 17 75 which extend through suitable openings in the float. A rack bar 36 extends upwardly from said float and into the casing 10. Movement of the rack bar is adapted to impart movement to computing mechanism 80 carried in the casing 10. This mechanism consists of a main shaft 38 which is secured in the casing 10 and has loosely mounted thereon a gear wheel 39, the latter carrying a spring pressed pawl 40. The pawl is adapted for engagement with a ratchet 41 which is fixedly carried by the shaft 38. The gear wheel 39 is in mesh with a pinion 42 which latter is carried by a stub shaft 43, the stub shaft carrying a gear wheel 44 which is in 85 mesh with the rack bar 36. From this construction it will be apparent that upward movement of the float will not impart movement to the shaft 38. Reversely, however, downward movement of the float will be 90 communicated through the train of gears to the shaft 38, causing rotation of the same and corresponding rotation of a graduated computing disc 45 which is carried thereby.

The gear 39 may also be connected with other mechanism if desired, such for instance, as a registering device to register the number of gallons of liquid dispensed from the measuring receptacle 9. On the upward movement of the float, the shaft 38 is held 100 from movement by a pawl 70 and ratchet 71, the former being pivoted to a fixed part, (not shown) in the casing 10, and the latter secured to the shaft 38.

The computing dial 45 has graduations 110

around its entire circumference, the aggregate of which may be any multiple of the capacity of the measuring chamber 9. The ratio of the gears 39, 42, 44 and rack bar 36 5 may be so arranged that a full downward stroke of the float 35 will cause only a fraction of a revolution of each gear wheel. Thus, the dispensing of the complete contents of the measuring receptacle will rotate 10 the dial 45 only a partial revolution. Consequently, should the measuring receptacle hold only ten gallons and a customer desired thirty gallons, three full receptacles could be successively dispensed and their 15 aggregate amounts indicated on the dial 45. However, if a customer should desire only a quantity equivalent to or less than the capacity of the measuring receptacle, or even if he receives one or more full measures of 20 the receptacle plus a fraction of the capacity of the latter, mechanism is provided to automatically return the dial to a neutral or zero position. This mechanism consists of a hook member 46, one end of which is sleeved on 25 a fixed shaft 47. The free end of the member is formed to provide a bill 48 which is adapted to receive a ring 49 attached to the end of a dispensing hose 18. The bill is normally held in its uppermost position by 30 a spring 50 which is convoluted on the shaft 47 and has one end secured to the member 46 and the other end engaged with a fixed part 51 of the casing 9.

An arcuate arm 52 is formed on the member 46 and has teeth on its inner margin which engage in mesh with a loosely mounted pinion 53. A disc 56 is loosely arranged on the shaft 38 attached to the pinion 53, is secured thereto, and carries a spring 55, 35 one end of which is turned outwardly to provide an abutment 54. A bell crank lever 57 is pivoted on the dial 45 and has one end normally held in the path of the abutment 54 by a spring 58. The opposite end of said 40 lever is in pivotal connection with a bolt 59 which is slidable through a sleeve 60. The bolt is limited in its movement in the sleeve 60 by an offset ear 61. One end of a strap 62 is secured directly above the sleeve 60 45 and is either secured to or made an integral part thereof. The free end of said strap is flexed outwardly from the dial 45 in superposed relation to the bolt 59 and has its terminal reversely folded to form a stop 63. 50 This stop will, at times, be in the path of movement of a lug 64, which is formed on the member 46, to stop movement of the dial in a manner subsequently set forth.

A charge indicating dial is carried by the 55 quantity indicating dial 45 and has charges inscribed thereon which are commensurate with and alignment with the registered amount of gasoline dispensed. Therefore, the quantity of gasoline and its charge will 60 be visualized through an opening 65 in a

cover plate 66, of the stand 7. This plate is removable to permit the charge indicating dial to be changed so as to harmonize with fluctuations in prices charged. The daily price of the gasoline will be displayed 70 centrally on the charge indicating dial as indicated at 67. This charge will be discernible through a transparent opening 68 in the cover plate.

As is no doubt apparent from the above, 75 gasoline is introduced into the receptacle 9 through the pipe 12. Action of the float 35 controls the dispensing of the liquid from the receptacle 9 through the discharge hose 18. While the gasoline is being dispensed from said receptacle through the discharge hose the computing mechanism automatically operates in the manner above described 80 so as to indicate the quantity and value of the liquid or gasoline dispensed. After the 85 liquid has been dispensed in this way the ring 49 of the discharge hose 18 is hung upon the bill 48 of the hook member 46. The weight of the discharge hose on said bill causes the member 46 to move downwardly in the arc of a circle, thus rotating the pinion 53 and disc 56 through somewhat more than a complete revolution. Since this pinion and disc are free to rotate on the shaft 38, this movement does not rotate said shaft 90 or the dial plate 45 as the latter is fixed to said shaft. In view of the fact that the dial 45 remains stationary after the discharge hose is hung on the hook, it will be 95 apparent that the quantity and value of the liquid dispensed will be discernible to the customers served, this indication being retained until the discharge hose is removed from the hook. However, as soon as the 100 discharge hose is removed from the hook to serve the next customer the spring 50 causes said hook member 46 to move upwardly, thereby rotating the spring 55 through an 105 arc somewhat in excess of a complete revolution. At some point during this movement, depending upon the position of the dial 45 at that time, the abutment 56 will engage the bell crank lever 57 and exert pressure thereon so as to impart movement to the dial 45, until the projection 63 comes 110 in contact with the lug 64, thus bringing the dial to a stop at the neutral or zero position. Since the upper face of the lug 64 is formed as an arc of a circle, drawn from the center of the shaft 47, it is obvious that although 115 the dial plate is brought to a stop, in the manner above set forth, said lug will be carried by the hook member 46 further upwardly along the lower lateral margin of the strap 62 and will impinge the outer end 120 of the sliding bolt 59. This bolt will be caused to move through the sleeve 60 thereby rotating the bell crank lever on its pivot to disengage it from the abutment 54 of the 125 spring 55. This will release the dial 45 and 130

- permit it to again rotate on the next downward movement of the float 35. Of course, during the upward movement of the hook member 46, the proportion of the parts will 5 permit the lug 64 to have movement sufficiently far to the right of the projection 63 to clear the latter. In this way danger of said projection being engaged by the lug during further rotation of the dial 45 will 10 be eliminated until the discharge hose has again been hung upon the hook. Also, as a precautionary measure, the projection 63 is resilient to permit its flexure if perchance the lug 64 should contact therewith when 15 the hook member 46 moves downwardly.
- Various changes may be made in this device, especially in the details of construction, proportion and arrangement of parts within the scope of the appended claims.
- 20 What is claimed is:
1. A quantity and value indicating means for liquid pumps including a receptacle equipped with mechanism automatically operated by diminution of the contents of 25 the receptacle, means controlled by said mechanism to indicate the quantity and value of the liquid dispensed from the receptacle, and secondary mechanism to render said indicating means inoperative when 30 refilling the receptacle.
  2. A quantity and value indicating means for gasoline filling pumps including a receptacle to receive gasoline and equipped with a float operable by influx of the gasoline 35 line into the receptacle, means operable by the float to indicate the amount of gasoline dispensed from the receptacle and means to return said indicating means after using the same, immaterial of whether the contents 40 of the receptacle has been dispensed in whole or in part, whereby another quantity of liquid may be dispensed from the receptacle and the amount indicated on the first said means.
  - 45 3. A quantity and value indicating means for gasoline filling pumps including a measuring receptacle for gasoline equipped with a float operable under influence of the gasoline, a computing dial in connection 50 with the float and operable by movement of the latter, said dial having graduations
- thereon, the aggregate of which may be any multiple of the capacity of said receptacle, whereby the receptacle may be successively filled and successively dispensed and the 55 aggregate amounts so dispensed indicated on the dial, and means in connection with said dial for returning the latter to a neutral position at the inception of each use of the pump.
4. A quantity and value indicating means for gasoline filling pumps including a measuring receptacle equipped with a float operable by movement of gasoline in the receptacle, computing mechanism operatively connected to the float to be controlled by movement of the latter, means releasable to permit operation of the computing mechanism to constantly indicate the quantity and value of the gasoline dispensed from said receptacle whether the quantity be the whole or 60 only a part of the contents of the receptacle.
5. A quantity and value indicating means for liquid pumps including a measuring receptacle equipped with a float operable by 65 movement of liquid in the receptacle, computing mechanism in connection with and operated by movement of the float to indicate the quantity and value of the liquid dispensed from the receptacle, releasing 70 means for said mechanism to permit functioning of the latter, means to lock the releasing means from further movement, disengagement of said locking means permitting the mechanism to return to a normal 75 position substantially as described.
6. A quantity and value indicating means for liquid pumps including a receptacle equipped with a dispensing hose, mechanism operable by diminution of the contents of 80 said receptacle to indicate the quantity and value of the liquid dispensed, said dispensing hose being engageable with the mechanism to retain the latter stationary for exhibiting the quantity and value indicia, and 85 auxiliary mechanism automatically operable, upon disengagement of said hose, to return the indicating means to a neutral position.

In testimony whereof we affix our seals.

EMORY SUDLER.

CHARLES E. SUDLER.
